UNITED STATES PATENT OFFICE.

THOMAS G. MOUAT, OF CLEVELAND, OHIO.

STEAM-GAGE.

1,128,805.

Specification of Letters Patent. Patented Feb. 16, 1915.

Application filed February 26, 1912. Serial No. 679,883.

To all whom it may concern:

Be it known that I, THOMAS G. MOUAT, a citizen of the United States, residing at Cleveland, in the county of Cuyahoga and State of Ohio, have invented a certain new and useful Improvement in Steam-Gages, of which the following is a full, clear, and exact description, reference being had to the accompanying drawings.

This invention relates to gages of the type that are employed with boilers for the purpose of indicating the steam pressure therein. These gages, as ordinarily used, are connected directly with the water space of the boiler and, when the pressure of steam is high, allow the water from the boiler to flow out through the gage, thereby affecting the water level.

It is the general object of this invention to provide a construction wherein the pressure will be accurately indicated and without affecting or being affected by the height of the water in the boiler; also to provide a construction which is comparatively simple and efficient in operation.

Still further and generally speaking, the invention may be defined as consisting of the combinations of elements embodied in the claims hereto annexed and illustrated in the drawings forming part hereof, wherein—

Figure 1 represents a view, partly in section and partly in elevation, showing my gage and the manner of connecting the same to a boiler; Fig. 2 is an enlarged vertical sectional view taken through the gage and Fig. 3 a bottom plan view of the gage.

Describing by reference characters the various parts illustrated herein, 1 denotes the shell of a boiler, the normal water level therein being indicated at 2. Above the water line, and preferably from a point near the top of the boiler, there projects a horizontal pipe section 3, which may be connected to the boiler in any convenient manner, being shown herein as clamped to the wall of the boiler by nuts 4 threaded on to the pipe section and abutting against the inner and outer surfaces of the boiler shell.

5 5 denotes a hollow reservoir preferably of substantially cylindrical form and having radial threaded connections projecting in opposite directions from the upper and lower parts thereof, to the upper of which is secured the outer end of the pipe section 3. The upper part of the reservoir is pref-

erably provided with a filling aperture normally closed by the plug 6, while to the bottom connection there is secured the gage fitting hereinafter described. In the present embodiment this gage fitting is supported by means of a nipple 7 and a connecting member 8, the latter being here shown as consisting of a three branched elbow. One of these branches receives the plug 9 of the gage fitting, said plug having a longitudinal bore 10 formed at its outer end with the valve seat 11 and normally communicating with a chamber 12 provided at the central part of the gage fitting. Opposite this plug 70 the gage fitting is formed with an internally and externally threaded tubular projection 13, said projection forming a support for a valve stem 14, which is threaded into said projection and is provided with a frusto-conical valve 15 coöperating with the valve seat and with a cylindrical extension 16 of substantially the diameter of the bore 10. A guide extension 17 is provided on the valve stem, which extension projects into 80 and through the bore 10 when the valve is seated and forms a guide for the valve when the valve is withdrawn a considerable distance from its seat. The valve stem 14 extends through a stuffing box having a gland nut 18 threaded onto the exterior of the tubular projection 13. Said gage fitting is also formed with an upwardly extending intermediate tubular projection 19 having an exterior thread and supporting a gage tube 90 20, the tube extending through a stuffing box comprising a gland nut 21 threaded onto the extension 19. At its upper end, the gage tube 20 is preferably provided with a metallic casing 22 which incloses the end of 95 the tube and is provided with a discharge outlet 23, the casing being secured to the tube through a stuffing box comprising a gland nut 24 threaded onto the lower end of the casing. A drain cock 25 is preferably provided for draining the reservoir and gage tube. Carried by the reservoir 5 is an upright rigid index plate 28, here shown as supported by means of a pipe nipple 27 threaded into the third branch 26 of the 100 elbow 8. This plate is provided with graduations 29 indicating the boiler pressure in the gage in terms of any convenient unit, as ounces. The plate 28 extends upwardly 105 preferably as high as the top of the gage tube 20 and is provided with a bracket 30, projecting laterally therefrom and through

which the upper portion of the gage tube 20 extends, whereby the said bracket forms a guide and support for the upper end of the tube. Rods 31 depending from the bracket 30 are connected to lugs 32 carried by the tee fitting so as to support the outer end of said fitting, the lower ends of the rods being provided with nuts 33 (see Fig. 3) by which they are secured to the lugs 32.

10 In operation, the reservoir 5 is filled with water through the plug 6, the level of the water being determined by the connection 3. This level is the same as the zero graduation on the index. The pressure of the steam in the boiler is transmitted to the reservoir 5, and the water is forced from said reservoir through the valve-controlled passageway 10 into the chamber 12 and thence into the gage glass 20, the height of 15 the liquid column in pressure terms being indicated by the graduations on the index plate. The reservoir 5 will be of such large cross-sectional area compared with that of the gage 2 that a comparatively slight depression of the liquid level in the reservoir 20 will fill the gage tube. Should the pressure of steam in the boiler become unusually high, water will be forced from the reservoir out of the gage tube, the tube constituting a safety valve for the boiler.

30 By locating the reservoir in the manner shown and described herein, the reservoir will normally keep filled through the condensation of steam within the top of the reservoir, while the level of liquid cannot extend above the bottom of the tubular connection 3 since water accumulating above this line will flow into the boiler.

Having thus described my invention, what 40 I claim is:

1. The combination, with a steam boiler, of a reservoir communicating with the steam space of the boiler at a point above the bottom of the reservoir in such manner as to provide an overflow for water of condensation from the reservoir to the boiler, a threaded connection carried by said reservoir and communicating with the interior thereof at a point below the point of connection of said reservoir with said steam space, a fitting carried by said connection, an upright gage tube of transparent material carried by said fitting, the upper end of said gage tube being in communication with the atmosphere, means for closing the passage between said gage tube and said reservoir, a supporting member carried by said fitting, and an index plate carried by said supporting member adjacent to and parallel 50 with said gage tube.

60 2. The combination, with a steam boiler, of a reservoir communicating with the steam space of the boiler at a point above the bottom of the reservoir in such manner as to provide an overflow for water of condensa-

tion from the reservoir to the boiler, a connecting member communicating with the reservoir below the point of connection of the reservoir with the boiler and having vertical and lateral branches, a gage fitting secured to one of said branches, means for closing the passage through said gage fitting, a vertically arranged gage tube of transparent material joined to said gage fitting, and an index plate supported by said vertical branch and coöperating with said gage tube.

70 3. A gage comprising, in combination, a substantially horizontal elbow having a vertical branch at the junction of its lateral branches, a tee fitted in one of the lateral branches of the elbow and having a bore therethrough, a valve mounted in the opposite branch of the tee and adapted to control said bore, a gage tube of transparent material projecting upwardly from the vertical branch of the tee, an index plate co-operating with the gage tube and supported by the vertical branch of the elbow, and connections for supplying liquid to the lateral branch of the elbow opposite the valve controlled branch.

75 4. A pressure gage for vapor boilers comprising a hollow reservoir having horizontally projecting threaded connections at its upper and lower portions, means for attaching the upper of said connections to a steam boiler in such a manner as to place the same in communication with the steam chamber thereof and to provide an overflow 80 for water of condensation from the reservoir to the boiler, a gage fitting communicating with the other of said connections and having an upwardly projecting extension, an upright gage tube of transparent material carried by said extension, the upper end of said gage tube being in communication with the atmosphere, an indicator plate rigid with said reservoir and projecting upwardly parallel with said gage tube, and a lateral bracket carried by 85 said plate at a point removed from its lower end and having an aperture loosely receiving said gage tube, the horizontal cross sectional area of said reservoir being 90 very large as compared with that of the tube.

95 5. A pressure gage for vapor boilers comprising a hollow reservoir having horizontally projecting threaded connections at its upper and lower portions, means for attaching the upper of said connections to a steam boiler at a point above the water line thereof in such a manner as to provide an overflow 100 for water of condensation from the reservoir to the boiler, a gage fitting communicating with the other of said connections and having an upwardly projecting extension, an upright gage tube of transparent material carried by said extension, the up- 105

per end of said gage tube being in communication with the atmosphere, a rigid indicator plate carried by said reservoir and projecting upwardly parallel with said 5 gage tube, said reservoir having a horizontal cross-sectional area very large as compared with that of the tube and also having a filling opening in its upper part, means for closing said opening, and a drain cock 10 communicating with the lowest part of said tube.

6. The combination, with a steam boiler, of a hollow cylindrical reservoir having radial threaded connections projecting in opposite directions from the upper and lower 15 portions thereof, a horizontal pipe secured in the upper of said connections and communicating with the steam space of the boiler, a gage fitting communicating with 20 the lower of said connections and having an upwardly extending projection, a rigid ver-

tical plate carried by said reservoir and having a lateral bracket formed with an aperture above and in line with said projection, a gage tube of transparent material secured 25 to said projection and extending loosely through said aperture, the upper end of said gage tube being in communication with the atmosphere, means for closing the passage between said reservoir and gage tube, the 30 horizontal cross sectional area of said reservoir being very large compared with the cross sectional area of said tube and said plate being formed with graduations whose zero point coincides substantially with the 35 lower wall of said pipe.

In testimony whereof, I hereunto affix my signature in the presence of two witnesses.

THOMAS G. MOUAT.
